(57) **CLAIM**

The ornamental design for a torch head, as shown and described.

DESCRIPTION

FIG. 1 is a top perspective view of a torch head of the present invention;

FIG. 2 is a left side view thereof, the right side being a mirror image;

FIG. 3 is a top view thereof;

FIG. 4 is a bottom view thereof;

FIG. 5 is a front view thereof; and,

FIG. 6 is a rear view thereof.

The ornamental design which is claimed is shown in solid lines in the drawings. Any broken lines in the drawings are for illustrative purposes only and form no part of the claimed design.
